US00D932433S

(12) **United States Design Patent** (10) Patent No.: **US D932,433 S**
 Tang et al. (45) Date of Patent: ** Oct. 5, 2021

(54) **ENERGY STORAGE AND POWER SUPPLY DEVICE**

(71) Applicant: **SHENZHEN GREENERGY TECHNOLOGY CO., LTD.**, Shenzhen (CN)

(72) Inventors: **Luowei Tang**, Shenzhen (CN); **Hao Yu Liu**, Shenzhen (CN); **De Ding Cao**, Shenzhen (CN)

(73) Assignee: **SHENZHEN GREENERGY TECHNOLOGY CO., LTD.**, Shenzhen (CN)

(**) Term: **15 Years**

(21) Appl. No.: **29/765,268**

(22) Filed: **Jan. 7, 2021**

(51) LOC (13) Cl. **13-02**

(52) U.S. Cl.

USPC **D13/110**

Primary Examiner — Rosemary K Tarcza

(57) **CLAIM**

The ornamental design for an energy storage and power supply device, as shown and described.

DESCRIPTION

FIG. 1 is a perspective view of an energy storage and power supply device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the energy storage and power supply device that form no part of the claimed design.

1 Claim, 8 Drawing Sheets
